LOCK OPERATING MEANS FOR AUTOMOBILES

Arthur Wiebe, near Salinas, Calif.

Application June 26, 1935, Serial No. 28,497

1 Claim. (Cl. 70—14)

The present invention relates particularly to means for locking and unlocking a plurality of locks from one given point.

Having reference to one particular application of the invention, it is to be noted that in the modern automobile of the closed car type such as the sedan, each door is provided with a latch operated by means of a handle disposed upon the outside of the door and also by means of a handle disposed upon the inside of the door so that the door may be opened either from the inside or the outside of the car.

It is also common practice to provide at least one door with a key controlled lock, but this locking of the one door is of no value if the driver neglects to see that all of the other doors are likewise fastened.

To effect the fastening of the other doors a special locking device is provided for each latch, each such device being operative only from the inside of the car. Consequently before locking the key controlled lock it is necessary for the driver to reach each of the other doors from the inside of the car and operate the latch locking device referred to.

Obviously, when the driver returns and opens the door fitted with the key controlled lock he must reach each of the other doors from the inside in order to unlock them.

The door locking means above referred to is not only inconvenient for the driver, but very often is the cause of a great deal of trouble particularly when the driver attempts to open the several doors while loaded with packages.

It is, therefore, one object of my invention to provide means whereby all of the doors on a car may be simultaneously locked or unlocked as the case may be through the operation of but one key.

It is also an object of the invention to provide means of the character indicated that will not interfere with the normal operation of the door latches.

It is another object of the invention to provide means of the character indicated that will be simple in form and construction, economical to manufacture, that consists of few parts, is positive in operation, and highly efficient in its practical application.

In the drawing:

The figure is an illustration of a catch and locking means therefor embodying my invention, part being shown in section and part being broken away.

Referring now more particularly to the drawing, I show at 1 a part of the housing of a

common form of automobile door latch. In this housing is the bolt 2 urged into an operative position by a spring 3. The bolt 2 may be retracted by an operator within the car by means of a lever 4 pivoted on housing 1 at 5 and operating against an ear 6 on the said bolt. The said bolt 2 may also be retracted from the outside of the door by means of a handle and spindle 7, the spindle engaging a finger 8 operating against a finger 9 on the bolt 2.

To prevent opening the door from the outside a locking device is provided that is rendered operative only from the inside of the car. In the present instance this device comprises a pawl 10 pivoted on the housing 1 as at 11 and having two arms as 12 and 13. The arm 12 has a seat 14 formed thereon engageable with a similar oppositely disposed seat 15 on the collar 16 carrying arm or finger 8. The pawl is thrown into and out of engagement with the seat 15 by means of a lever 17 pivotally mounted in housing 1 as at 18 and carrying a finger 19 engaging the arm 13 as at 20.

In the above described structure the bolt 2 may, under normal conditions, be freely retracted by any one on the outside of the car by manipulating the handle and spindle 7, and such manipulation of the bolt from the outside of the car can only be prevented by the individual adjustment of the locking device 10.

In carrying out my invention I provide a master hydraulic cylinder as 21 and mount it in any convenient position in the automobile body.

In each latching mechanism I incorporate a small hydraulic cylinder as 22, connecting the same with the master cylinder by means of a suitable conduit 23. The cylinder 22 is so mounted in the latch mechanism that its piston 24 bears against the back of arm 12, consequently when the piston is advanced the arm 12 is moved into locking engagement with the seat 15 to prevent operation of handle 7.

In the present instance the weight of the arm 12 overbalances the rest of the pawl so that when the piston 24 is withdrawn it falls away from the seat 15 and the handle 7 is released.

It will be noted that this control also permits the pawl to be moved to operative position by the control 17. This individual control of the pawl is desirable since by means of it a passenger may be protected from annoyance by an intruder when the car is moving along the street without locking the other doors of the car.

Mounted in the car body adjacent the master cylinder 21 is a key controlled lock 25, this lock

being so disposed that when the bolt 26 is thrown out it will contact and actuate the piston 27 of cylinder 21 and through it actuate all of the smaller cylinders, as 22, to simultaneously and positively lock all of the latches. Reversing the operation and retracting the bolt 26 releases the piston 27 for reverse movement.

In the present case the end of the master cylinder 21 through which the piston 27 projects is fitted with a cap 28 provided with an opening 29 through which the piston 27 projects. A cylinder 30 is movably fitted over the end of the piston 27 and is provided with a flange 31 at one end seating against the inside of the cap 28 as shown the other end being closed by a wall 33. Mounted within the cylinder 30 and abutting the end of piston 27 is a spring 32.

Since this part 30 with spring 32 is inserted between the piston 27 and bolt 26 it follows that the pressure from the bolt 26 is conveyed through the said spring 32 and the pressure is built up uniformly yet quickly and positively.

It is to be understood, of course, that while I have herein shown and described but one specific embodiment of the invention, changes in form, construction, and method of assembly and operation may be made within the scope of the appended claim.

I claim:

In a device of the character described, the combination of an hydraulic cylinder provided with a projecting piston, a member mounted on one end of said cylinder to overlie the adjacent piston end, a cylinder having a closed end movably fitted over and resiliently seated on said piston end, and projecting beyond said member, stop means inserted between the cylinder and member, and a key controlled lock having a projectable bolt operatively disposed adjacent the hydraulic cylinder with its bolt engaging the closed end of the second cylinder whereby projection of the bolt will actuate the piston.

ARTHUR WIEBE.
